Assistant Examiner — Giang Hoang Tran

(57) **CLAIM**

I claim the ornamental design for a modular paddle, as shown.

DESCRIPTION

FIG. 1 is a front view of the modular paddle.

FIG. 2 is a rear view of the claimed design.

FIG. 3 is a right side view of the claimed design.

FIG. 4 is a left side view of the claimed design.

FIG. 5 is a top view of the claimed design.

FIG. 6 is a bottom view of the claimed design.

FIG. 7 is an exploded perspective view of the claimed design; and,

FIG. 8 is an assembled perspective view of the claimed design.

1 Claim, 7 Drawing Sheets(56)
